UNITED STATES PATENT OFFICE.

KIRK BROWN, OF MONTCLAIR, NEW JERSEY, ASSIGNOR TO CONDENSITE COMPANY OF AMERICA, OF BLOOMFIELD, NEW JERSEY, A CORPORATION OF NEW JERSEY.

APPARATUS AND PROCESS INVOLVED IN CHLORINATION.

1,294,230.

Specification of Letters Patent. Patented Feb. 11, 1919.

Application filed May 17, 1917. Serial No. 169,185.

To all whom it may concern:

Be it known that I, KIRK BROWN, a citizen of the United States, residing at Montclair, in the county of Essex and State of New Jersey, have invented certain new and useful Improvements in Apparatus and Processes Involved in Chlorination, of which the following is a specification.

My invention relates to improvements in apparatus designed for chlorinating naphthalene, or for carrying out other chemical operations in which vapors pass from one reaction vessel to another, which vapors must be constantly maintained in a heated condition. In such operations, there is always the danger that the vapors will cool sufficiently to solidify and choke up the pipes and valves connecting the various pots or reaction vessels in the system. My invention overcomes this difficulty by inclosing the valves and a considerable portion of the piping within the chlorinating or reaction vessels, so that the actual passage between adjacent vessels is reduced to a few inches of pipe only.

In the chlorination of naphthalene, for which the invention is chiefly designed, the process is carried out by passing chlorin gas successively through a series of pots or reaction vessels containing molten naphthalene. The chlorin gas, or hydrochloric acid gas, which results from its reaction upon the naphthalene, carries with it the vapors of naphthalene in its passage from one pot to the next. It is necessary that communication between these pots should be shut off from time to time, and, accordingly, in the usual system, the pots are connected by pipes, each of which is provided with a valve. To prevent solidifying of the naphthalene vapors within the pipes and valve passages, steam-jacketing is ordinarily employed and this is both troublesome and expensive. These difficulties are entirely overcome by my invention in which the heating means for the pots or reaction vessels themselves are used to prevent fall of temperature in the piping and valves. The greater part of the piping and the valves are entirely within the vessels, as stated, preferably adjacent to steam-jacketed surfaces of the pots. The short length of piping between adjacent pots need not be steam-jacketed because it may be kept sufficiently warm by the heat from the adjacent pots, a simple connection between the pots being suffi-

cient to house the piping extending through the same.

Another feature of my invention relates to the recovery of naphthalene from the gases which are carried off at the end of the chlorinating process, and the consequent cleaning of these gases for subsequent recovery, as described hereafter.

In order that a clearer understanding of my invention may be had, attention is hereby directed to the accompanying drawings forming part of this specification and illustrating certain embodiments of my invention. In the drawings, Figure 1 represents somewhat diagrammatically a side elevation of a series of three chlorinating pots connected for operation, Fig. 2 is an enlarged vertical section through the adjacent portions of a pair of pots, and Fig. 3 is a diagrammatic side elevation of a series of chlorinating pots with means for separating naphthalene from the gases at the end of the process.

Referring to the drawings, the chlorinating pots are illustrated at 1, 2 and 3, it being understood that any desired number may be used. These pots are steam-jacketed, preferably on the bottoms and about their sides, as indicated at 4, 5 and 6. Naphthalene or other material to be chlorinated is led into the system, preferably from one end, until the same stands in fluid condition at a desired level in all of the pots, after which chlorin gas is pumped through the system, preferably from the other end. In the drawings I have diagrammatically indicated a tank at 7, from which naphthalene flows through a pipe 8, provided with a valve 9, into the pot 1, while I have indicated at the opposite end of the system a pipe 10 through which chlorin is pumped below the surface of the naphthalene in pot 3. These pots are kept closed during the operation and may be provided with covers 100 11 secured in any desired manner.

The connection between each pair of pots, such as 2 and 3 and 1 and 2, is made by a suitable pipe 12, which preferably is made in two sections, one in each pot, the ends of which are joined by a union or coupling 13, which is flanged and is suitably secured to flanges 14 and 15 on the adjacent pots. The sections of pipe 12 may be secured to the coupling by providing coacting screw-threads 16, and the coupling 13 may be provided with a suitable draw-off plug 17.

Referring to Fig. 2, the pipe 12 extends within pot 2 horizontally and closely adjacent to the steam-jacketed bottom to its end 18. In the adjacent pot 3 the pipe 12 is provided with an elbow 19, from which rises a vertical pipe 20, providing a valve seat at its upper end, above the normal level of the naphthalene. A valve is provided having a part 21 to coact with this valve seat 10 and to control the opening in the top of pipe 20. This valve is entirely within the pot 3 and is operated from the exterior of the pot by any suitable means, such as the valve stem 23 extending upwardly through a suitable gland in the cover, this valve stem being adapted to be raised and lowered through the standard 24 in which it is screw-threaded by means of a hand-wheel 25.

Any suitable form of valve may be used, 20 but I prefer the form of lift valve illustrated, in which the lower end of stem 23 is provided with an enlarged and rounded portion 22, engaging in a suitable opening in valve 21, to form a universal connection of 25 limited movement, so that the valve may seat itself on its seat without the necessity of an exact alinement of pipe 20 and valve stem 23. It will be noted that pipe 20 is shown as mounted adjacent to a steam-jacketed 30 surface of pot 3. While this position is incidental to the construction in which the rest of the space is largely filled by baffle plates, it will be noted that the steam-jacket insures the pipe 20 being kept heated.

35 The pots are illustrated as provided with series of superposed pans 26, as is usual in chlorinating apparatus. The chlorin gas is pumped into pot 3 through a pipe extending through a connection 13 similar to the 40 connections between adjacent pots. The chlorinated product may be drawn off or removed from any pot in any desired manner, as by drawing the same off through connection 27 which may also be used for the purpose of drawing off samples.

In the usual operation, chlorine gas entering pot 3 passes through the naphthalene therein, some of the chlorin gas, together with hydrochloric acid gas, passing through 50 the valve and pipe connections to pot 2, and some of the gas similarly passing through the valve and pipe connections in pot 2 into pot 1. When the material in pot 3 has been chlorinated to a desired stage, the supply of 55 chlorin gas passing through pipe 10 is stopped, the valve 21 in pot 3 is closed and the chlorinated product removed from pot 3, after which the partially chlorinated product in pots 1 and 2 may be blown over 60 or otherwise transferred to pots 2 and 3 and pot 1 refilled with naphthalene to be chlorinated, after which the operation may be repeated. The above is, of course, merely illustrative of the use of the apparatus.

65 Another part of my invention, as stated,

consists in the method and means of freeing the gas, after its passage through all the chlorinating pots of the system, from the naphthalene vapors which its carries. As stated, the gas passing from pot 3 to pot 2 70 and on through the series of pots used carries naphthalene vapors with it. These can be removed by passing the gas through a solvent for the naphthalene, at a temperature low enough to condense the naphthalene vapors. I prefer to use mono-chloro-naphthalene for the solvent, as this is a liquid at room temperatures, and when it has absorbed as much naphthalene from the gases as is advisable, it can be transferred 75 into one of the chlorinating pots as a desirable starting material for the chlorination process.

In Figs. 1 and 2 the chlorinating apparatus only is shown. In Fig. 3 I have indicated diagrammatically a series of two chlorinating pots, 3 and 2, similar to those already described, it being understood that as many steam-jacketed pots are used as is desirable. Chlorin gas enters pot 3 at 10 80 as before, and some chlorin gas, together with some hydrochloric acid gas from the reaction with the naphthalene, passes over through pipe 12 into pot 2. The gas which collects in the upper part of pot 2 contains a 85 larger percentage of hydrochloric acid gas, and in a suitably designed series of pots may be all hydrochloric acid gas at the end of the series.

This gas passes through valve 22 and pipe 100 12', into the vessel or pot 28, which is preferably cooled by being water-jacketed, and contains liquid chloro-naphthalene which may be mono-chloro-naphthalene 29. This pot does not require the baffle plates 26, and 105 it may be termed a scrubber. Pipe 12' should end at the point where it enters the scrubber, as otherwise the naphthalene carried by the gas would deposit therein and choke it up. The hydrochloric acid gas 110 which rises from the surface of this mono-chloro-naphthalene is freed from the naphthalene carried over with it into the scrubber, and passes off at 30, in purified condition, to be recovered. The successful operation 115 of this system depends considerably upon bringing the hydrochloric acid gas to the scrubber in its heated condition, so that it will not deposit its naphthalene until it gets into the relatively cold scrubber. 120

The process is continued until the liquid in the scrubber has absorbed enough naphthalene to be no longer freely fluid, when it is removed, and preferably transferred to one or more of the chlorinating pots, the 125 scrubber 28 then being refilled with mono-chloro-naphthalene, or the system being connected up with a reserve scrubber. The contents of the scrubber are preferably transferred to the chlorinating pots by blow- 130

ing it back through the system. I have illustrated the scrubber diagrammatically as provided with a pipe 31, for admitting liquid chloro-naphthalene from a tank 32, 5 pipe 31 having a connection 33, for admitting air from a blower for transferring the liquid to pots 2 and 3, the chlorin admission pipe 10 being closed. The chlorinating pots may be provided with sufficient excess 10 capacity to enable them to receive this charge. The pot 2 is represented as provided with a connection 8 to a naphthalene tank 7, in which naphthalene is heated to liquefy the same, and a connection 34 to the blower, for transferring the contents of pot 2 to pot 1, when the latter is to be refilled.

One advantage of this method is that thereby the chlorinating pots may readily be filled with starting material when a chlorinated product higher than the mono is desired. With the method described, the mono-chloro-naphthalene serves to prevent the loss of naphthalene, to clean the hydrochloric acid gas produced, and to serve as a part 20 of the starting material, for the chlorinating pots, after it has performed its function in the scrubbers.

What I claim is:—

1. In chemical apparatus, the combination 30 of a pair of normally closed chlorinating vessels, closely adjacent to each other, means for introducing material to be chlorinated into one of the same, a pipe connecting said vessels, having one end within the lower portion of said first vessel, an upwardly extending pipe entirely within the second vessel, connected therein with said first pipe, a valve at the upper end of said second pipe, means for operating the same from the exterior of the vessel, to open and close the same, means for heating said vessels, and means for introducing chlorin into said second vessel, substantially as set forth.

2. In chemical apparatus, the combination 45 of a pair of normally closed reaction vessels, a pipe connecting the same, having one end within the lower portion of one vessel, and the other end within the other vessel, the end last mentioned being provided with a valve seat, a valve coacting therewith, within said vessel, means for operating the same from the exterior of the vessel, and means for maintaining said vessels in heated condition, said second vessel having an admission pipe leading into the same, substantially as set forth.

3. In chemical apparatus, the combination 50 of a pair of normally closed reaction vessels, a pipe connecting the lower portions of the same, having one end within the lower portion of one vessel, and having an upwardly extending portion within the sec-

ond vessel, terminating in a valve seat, a valve adapted to seat on said valve seat, within said vessel, a valve stem extending therefrom to the exterior of the vessel, and means for maintaining the portions of said vessels in which the said lengths of piping are arranged, in a heated condition, said second vessel having an admission pipe leading into the lower portion of the same, substantially as set forth. 70

4. In chemical apparatus, the combination of a pair of normally closed steam-jacketed reaction vessels, a coupling connecting the same, pipe sections connected with said coupling, and extending within said vessels adjacent to steam-jacketed surfaces thereof, to their opposite ends, a valve seat at one of said ends, a valve therefor, 75 means for operating the valve from the exterior of the vessel, and an admission pipe leading into said last-named vessel, substantially as set forth. 80

5. In chemical apparatus, the combination of a series of vessels for chlorinating naphthalene, means for passing chlorin gas successively through the same, means for heating the same, a vessel for containing liquid chloro-naphthalene, the lower part of 85 which is connected with the gas space of the last chlorinating vessel of the series, a pipe for leading gas from the upper part of said last named vessel, means for supplying liquid chloro-naphthalene thereto, and 90 means for supplying melted naphthalene to said chlorinating vessels, substantially as set forth. 95

6. In chemical apparatus, the combination of a pair of normally closed reaction vessels, means for heating the same, a pipe connecting the same having one end within the upper part of one vessel and the other end within the lower part of the second vessel, a third vessel adapted to hold liquid, a pipe connecting the upper part of the second vessel with the lower part of the third vessel, valves in said pipes, a gas admission pipe leading into the lower part of the first vessel, a gas exit pipe leading from the upper part of the third vessel, means for forcing the contents of the third vessel into the second and first, means for forcing the contents of the second into the first, means for introducing liquid into the second and first, and means for introducing a different liquid into the third, substantially as set forth. 100 105 110 115

This specification signed and witnessed this 10th day of May, 1917.
